UNITED STATES PATENT OFFICE.

CHARLES THOMPSON, OF CORVALLIS, OREGON.

D R A G - S A W .

SPECIFICATION forming part of Letters Patent No. 271,159, dated January 23, 1883.

Application filed August 26, 1882. (Model.)

To all whom it may concern:

Be it known that I, CHARLES THOMPSON, of Corvallis, in the county of Benton and State of Oregon, have invented a new and Improved 5 Drag-Saw, of which the following is a full, clear, and exact description.

My invention consists of a novel contrivance of foot-levers or treadles, a hand-lever, and a seat-lever, whereby the operator may 10 use the power of his weight on the treadles and of his hands on the hand-lever for working the saw in one direction, and the power of his weight on the seat-lever and of his hands on the hand-lever for working the saw in the 15 reverse movement, thus enabling a greater exercise of power than is afforded by other machines; and the invention also consists of a contrivance of the seat for greater comfort of the operator, all as hereinafter fully described.

Reference is to be had to the accompanying drawings, forming part of this specification, in which similar letters of reference indicate corresponding parts in both the figures.

Figure 1 is a perspective view of my improved sawing-machine, and Fig. 2 is a detail of the log-fastening device in section.

For mounting the saw and the working-levers I employ a frame consisting of posts *a* and horizontal beams *b*, together with a base, 30 *c*, or not, as preferred, the beams being attached at one end to the posts, and at the other end having an adjustable stay-post, *d*, and foot *e* for resting on and securing the log *f* by a dog, *g*.

35 The saw *h* has a rigidly-attached shank, *i*, which is pivoted to the lower end of a working-lever, *j*, which has its fulcrum on a rod, *k*, mounted in the posts *a* at the top. This working-lever has the hand-lever *l*, pivoted to its upper end, and said hand-lever has its fulcrum on the end of the bar *m*, which is pivoted to the frame at *o* to enable the fulcrum of the hand-lever to vibrate as the swing of the working-lever demands.

45 The seat-lever, which consists of the two parallel bars, *p*, cross-bar *q*, and seat *r*, is pivoted to the posts *a* at *s* below the fulcrum-rod *k* of the working-lever, with the seat projecting rearwardly from said posts suitably for 50 the operator sitting thereon to work the hand-

lever, and also to work foot-levers *t*, pivoted to the frame at *u*, and arranged with relation to the seat and the seat-levers, as shown, whereby the operator may apply his feet to the foot-pieces *v*, rigidly attached to levers *t*, said levers being connected to the seat-levers *p* by the rods *w* and the brackets *x*, and the seat-levers being connected to the working-lever *j* by the bar *y* and bracket *z*, so that when the operator shifts his weight from the seat to the foot-levers he may also pull on the hand-lever, and thus apply both powers for pulling the saw back, and when transferring his weight to the seat he may at the same time push on the hand-levers, and thus employ both of these powers for thrusting the saw forward. The hand-lever working both ways, together with the seat-lever working one way and the foot-levers working the other way to impel the saw, thus enables two powers to apply to the saw each way, by which the operator may exercise a greater amount of force by a given amount of effort than with other arrangements.

I employ the parallel bars *p* and cross-bar *q* for the seat-lever in order to arrange the seat 75 between them for enabling the operator to work between them with more comfort than he can astride of a single lever, and I pivot the seat in said bars at *a'* rather than attach it rigidly, so that it can vibrate, and thus maintain the 80 best relations to the operator for his comfort.

The leg *d* is adjustable vertically in the frame *b*, for shifting it up and down to suit the height of the log *f*, and is provided with a set-screw, *b'*, for securing it in position.

85 Braces *b''* may be employed to connect posts *a* and beams *b* for increased strength, and the seat-bars *p* have a series of holes, *a'*, in any opposite pair of which the seat-pivots *a'* may be secured to adjust the leverage of the rocking seat to suit the weight and strength of different operators.

Having thus described my invention, I claim as new and desire to secure by Letters Patent—

1. In a sawing-machine, the saw *h*, with its 95 shank *i*, connected to the lever *j*, secured to a shaft near its upper end, said shaft bearing in the supporting-frame, the hand-lever *l*, connected to the lever *j*, and the link or bar *m*, connecting the hand-lever *l* to the supporting- 100

frame, in combination with the seat-lever $p\ q$, connected to the lever j by the link y , and the foot-levers $t\ v$, suspended from the supporting-frame and connected to the seat-lever by the rods $w\ w$, substantially as and for the purpose set forth.

2. In a sawing-machine, the combination of the frame $a\ b$, having at its rear end the stay d , provided with the dog g , saw h , connected to the lever j , pivoted in the said frame, and

having the hand-lever l , the link or bar m , connecting the lever l to the frame, the seat-lever $p\ q$, connected to the lever l by the link y , and the foot-levers $t\ v$, suspended from the frame and connected to the seat-levers by the rods $w\ w$, substantially as and for the purpose set forth.

CHARLES THOMPSON.
